FERMENTATION TUBE FOR THE MANUFACTURE
OF WINE, VINEGAR CULTURES AND THE LIKE

Svend A. Poulsen, 3 Lindbjergvej,
2750 Ballerup, Denmark

Filed Feb. 28, 1969, Ser. No. 15,966

Term of patent 14 years

Int. Cl. D24—02

U.S. Cl. D16—1

FIG. 1 is a front perspective view of a fermentation tube for the manufacture of wine, vinegar cultures and the like, showing my new design;

FIG. 2 is a front elevation thereof;

FIG. 3 is a side elevation thereof; and

FIG. 4 is a top plan view thereof.

I claim:

The ornamental design for a fermentation tube for the manufacture of wine, vinegar cultures and the like, as shown.
